(57) **CLAIM**

The ornamental design for an analyzer table having a front portion with a tray, as shown and described.

DESCRIPTION

FIG. 1 is a front perspective view of an analyzer table having a front portion with a tray in accordance with our new design;

FIG. 2 is a front elevational view of the analyzer table having a front portion with a tray illustrated in FIG. 1;

FIG. 3 is a rear elevational view of the analyzer table having a front portion with a tray illustrated in FIGS. 1 and 2;

FIG. 4 is a right side elevational view of the analyzer table having a front portion with a tray illustrated in FIGS. 1-3;

FIG. 5 is a left side elevational view of the analyzer table having a front portion with a tray illustrated in FIGS. 1-4;

FIG. 6 is a top plan view of the analyzer table having a front portion with a tray illustrated in FIGS. 1-5;

FIG. 7 is a bottom plan view of the analyzer table having a front portion with a tray illustrated in FIGS. 1-6; and,

FIG. 8 is a top plan view of the analyzer table having a front portion with a tray illustrated in FIGS. 1-7 with the front portion and the tray rotated to an open position.

The broken line showing in FIGS. 1 through 8 are for illustrative purposes only and forms no part of the claimed design.
